Viktor Entler

UNITED STATES PATENT OFFICE.

VIKTOR ENTLE, OF BREMEN, GERMANY.

AEROPLANE.

Application filed July 6, 1920. Serial No. 394,404.

To all whom it may concern:

Be it known that I, VIKTOR ENTLE, citizen of Italy, residing at Bremen, Germany, have invented certain new and useful Improvements in Aeroplanes, of which the following is a specification.

My invention relates to improvements in aeroplanes. The principal object thereof is to provide a base-frame, on which the different parts of the aeroplane, as the motors with tanks, seats, supporting planes, body, wheel-framework, etc. and the like are supported.

This base-frame forms the support for the whole aeroplane and its body in contradistinction to known constructions in which the aeroplane is constructed on the body as a support.

The said base-frame may also be used for supporting passenger-cabins and other parts and in the case of aeroplanes with a plurality of motors the latter may be supported by extensions of the base-frame.

My said invention further comprises the combination and arrangement of parts hereinafter more fully described and pointed out in the claim.

Referring to the accompanying drawings Fig. 1 is an elevation of an aeroplane constructed according to my invention, Fig. 2 is a cross or end-view of the same, certain parts being omitted and Fig. 3 is a top view partly broken away.

In this embodiment the base-frame is built up of two framework-beams, the top-beam *a* and the bottom-beam *b*, which are rigidly connected to each other. The beams are connected by struts *c* and the framework so formed is connected and stiffened by cross-struts *d* and diagonal struts *e*.

Into this framework, forming the base-frame are mounted the motor *f* and its appurtenant parts as the steering device *g*, the seat *h* and the tank *i*. The lower supporting plane *k* is fixed to the lower-beam at *l* and *m*. In the like manner is the wheel-framework *n* secured to the base frame at *l* and *o*.

The tower *g*, to which the upper supporting plane *p* is fastened at *r* and *s*, is also secured to the base frame. The body *t* surrounds the base-frame and is fixed thereto by any suitable securing devices which are not illustrated as they are well known in and of themselves.

The body may be constructed of two parts, which may be detachable.

The advantage of the aeroplane-construction according to my invention is that the body is free from the great strains produced when the aeroplane rises and because it is possible to remove it from the base-frame, whereby all parts of the interior are freely accessible. The body forms a cover for the said base frame.

The invention is not restricted to the embodiment shown in the drawings, changes being possible without departing from the spirit of the invention.

I claim:

In an aeroplane a body, a supporting plane, a motor and a frame-work constituting an independent unit separate from the body, the frame-work supporting the body, the supporting plane and the motor, the said body being made of two parts which are detachable from the said frame-work.

VIKTOR ENTLE.
